DESIGN FOR A SHOE SOLE

Joseph E. Cox and William E. Kavenagh, Windsor,
Vt., assignors to Wingfoot Corporation, Wil-
mington, Del., a corporation of Delaware

Application October 31, 1940, Serial No. 96,223

Term of patent 14 years

To all whom it may concern:

Be it known that we, Joseph E. Cox and William E. Kavenagh, citizens of the United States, residing at #65 Union St., and 38 Ascutney Street, respectively, Windsor, in the county of Windsor and State of Vermont, have invented a new, original, and ornamental Design for a Shoe Sole, of which the following is a specification, reference being had to the accompanying drawing, forming part thereof.

Fig. 1 is a plan view of a shoe sole showing our new design; and

Fig. 2 is a longitudinal sectional view on line 2—2 of Fig. 1.

We claim:

The ornamental design for a shoe sole, as shown.

JOSEPH E. COX.
WILLIAM E. KAVENAGH.
